US00D585862S

(12) **United States Design Patent**
Holmung

(10) **Patent No.:** **US D585,862 S**
(45) **Date of Patent:** **** Feb. 3, 2009**

(54) **HANDSET**

(75) Inventor: **Ingve Holmung**, London (GB)

(73) Assignee: **Nokia Corporation**, Espoo (FI)

(**) Term: **14 Years**

(21) Appl. No.: **29/297,553**

(22) Filed: **Nov. 13, 2007**

(51) LOC (9) Cl. **14-03**

(52) U.S. Cl. .... **D14/138 AD**

(58) **Field of Classification Search** D14/137, D14/138, 147, 191, 218, 247-248, 341-347, D14/496; D10/65, 78, 104; D13/168; D18/7; 455/556.1, 566, 575.1, 575.3; 345/169

See application file for complete search history.

(57) **CLAIM**

The ornamental design for a handset, as shown and described.

DESCRIPTION

FIG. 1 is a front perspective view of a handset showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is a front perspective view of the handset as shown in FIGS. 1-7 in an open, in-use configuration; and,

FIG. 9 is a front view thereof.

The broken lines in FIGS. 1, 2, 7, 8, and 9, immediately adjacent to the claimed areas, represent the bounds of the claimed design while all other broken lines are directed to environment and are for illustrative purposes only; the broken lines form no part of the claimed design.

1 Claim, 7 Drawing Sheets
